CLAIM

The ornamental design for a display container for jewelry, as shown and described.

DESCRIPTION

FIG. 1 is a perspective view of an assembled display container for jewelry having a unique configuration of the present design;

FIG. 2 is a front view of an assembled display container for jewelry having a unique configuration of the present design. The back view of the display container for jewelry is identical to the front view;

FIG. 3 is a side view of an assembled display container for jewelry having a unique configuration of the present design. The opposite side view of the display container for jewelry is identical to this side view;

FIG. 4 is a top view of a display container for jewelry having a unique configuration of the present design;

FIG. 5 is a bottom view of a display container for jewelry having a unique configuration of the present design;

FIG. 6 is a perspective, exploded view of a display container for jewelry having a unique configuration of the present design;

FIG. 7 is an alternative perspective, exploded view of a display container for jewelry having a unique configuration of the present design; and,

FIG. 8 is a side, section view of a display container for jewelry having a unique configuration of the present design.
